UNITED STATES PATENT OFFICE.

AUGUST R. LUSCHKA, OF CHICAGO, ILLINOIS, ASSIGNOR TO AMERICAN SLICING MACHINE COMPANY, OF CHICAGO, ILLINOIS, A CORPORATION OF NEW YORK.

SLICING-MACHINE.

1,069,274.

Specification of Letters Patent.

Patented Aug. 5, 1913.

Application filed April 5, 1912. Serial No. 688,596.

To all whom it may concern:

Be it known that I, AUGUST R. LUSCHKA, a citizen of the United States, residing at Chicago, in the county of Cook and State 5 of Illinois, have invented a certain new and useful Improvement in Slicing-Machines, of which the following is a specification.

My invention relates to improvements in slicing machines and is illustrated diagrammatically in one form in the accompanying drawings, wherein—

Figure 1 is a side elevation of the machine; Fig. 2 a section along the line 2—2 of Fig. 1; Fig. 3 a section along the line 3—3 15 of Fig. 1; Fig. 4 a section along the line 4—4 of Fig. 3.

Like parts are indicated by like letters in the drawings.

The usual slicing machine base A, in which 20 is mounted the driving shaft A¹ carrying the crank wheel A² supports the reciprocating table A³ on the guide rail A⁴. The vertical housing A⁵, bolted to the frame A, carries at its upper end the sleeve A⁶ in which is screw 25 threaded the bearing A⁷. The rotary knife A⁸ is mounted on the shaft A⁹ in the bearing A⁷ and is driven by a chain riding over the sprocket wheel A¹⁰ and driven from the drive shaft by any suitable means.

The bracket 30 B, bolted to the sleeve A⁶, carries pivotally mounted thereon the hub B¹ from which projects the arm B² and which has the opposed flat sides B³ in opposition to the plunger B⁴ outwardly pressed by the spring B⁵. 35 in the bracket B. The arm B² carries slidably mounted in its outer end the rod C held in position by any suitable means and carrying the slideable blocks C¹. The flexible curved deflector C² is supported at either

40 end on one of the blocks C¹, being held thereon by the screw C³ which also engages the rod C and holds the block in position. The rod C carries the curved guard C⁴ parallel with the edge of the knife and located just 45 outside of and a little in front of the cutting edge. This guard is provided at its lower end with the extension C⁴⁰ bent outwardly away from the knife and inwardly toward the carriage and terminating in a downward 50 extension C⁵ which engages the latch C⁶.

The latch C⁶ is mounted on a guard D which is bolted to the frame A and is located immediately in front of the carriage. The meat supporting foot or guide D¹ is mounted 55 on the guard D immediately in front of

the cutting edge of the knife and at substantially the same level as the upper edge of the carriage A³. This support is provided with a horizontal portion D² parallel with the top of the table and with an inclined portion extending downwardly therefrom and away from the knife. The split nut E is slidably mounted on the lower end of the rod C and clamped in position thereon by the screw E¹. The bracket E² which is rotatably mounted on the nut E by means of the screw E³ carries the flexible scraper or deflector E⁴ made preferably of fiber or some other non-resonant material, and having the sharpened chiseled edge E⁵ in contact with the inclined back of the cutting edge of the knife along an approximately radial line. The knife rotates in a clock-wise direction in the form as indicated, and therefore approaches the deflector downwardly and any particles which adhere to the knife will be scraped off by the deflector or scraper as the knife passes the chiseled edge.

I have shown a device as adapted to a very well known type of slicing machine, but it will be quite evident that it might be adapted to any suitable form of machine, and I wish, therefore, that my drawings be regarded as in a sense diagrammatic.

The use and operation of my device are as follows: When the driving wheel is turning, the knife rotates and the carriage reciprocates back and forth in front of the knife, bringing the meat in the usual manner against the rotating cutting edge. The meat slices pass between the cutting edge and the guard, and thus the guard protects the cutting edge against anything but the meat, but does not interfere with its action upon the meat, in view of the fact that the guard is placed in front of the cutting edge in such manner that there is space for the meat to pass between it and the knife. The flexible curved deflector which is carried by the guard supporting rod, contacts the knife along a curved line concentric with, but of slightly lesser radius than the cutting edge of the knife and this deflector operates to turn the slice as it is cut, away from the knife and cause it to fall outwardly and downwardly into any suitable tray or pan. This deflector thus prevents the passage of meat inwardly toward the axis of the knife, and guards the central portion of the knife and housing and prevents the introduction of meat into the machine.

of meat therein. The flexible fiber or hard rubber chisel-edged scraper which engages the inclined portion of the cutting edge of the knife, is mounted upon the same rod as the deflector and the guard, and its function is to scrape off of the knife blade any fine particles which might adhere to it, and otherwise would be carried into the knife housing where they would be discharged by centrifugal force from the knife. Thus by means of the scraper and the deflector, which operate in unison and perform similar duties at different positions of the knife, the knife housing and the knife are kept entirely clean and free from meat particles and grease which would otherwise accumulate in the housing and decay. The guard, deflector and scraper, being all mounted upon a central rotatably mounted vertical shaft, may conveniently be thrown out of opposition to the knife by merely rotating them. In order to do this, the downwardly projecting extension on the guard is lifted outwardly out of the latch or hook and the guard is then rotated, carrying with it the deflector and the scraper. The effective cutting edge of the knife is then exposed and may be cleaned. When it is desired to use the knife again in a slicing operation, the deflector is swung around until the downward extension strikes the inclined portion of the latch, when it will, owing to its elasticity, spring into the latch hook and be held in position, thus compressing the scraper and deflector against the back of the knife. These two parts are additionally held in position by the pressure of the spring-actuated plunger on the edge of the flat portion of the hub. They are therefore held against the knife by yielding means on either side.

The scraper I have indicated is made of fiber, wood, rubber or some other non-resonant material, since owing to the rapid movement of the knife and owing to the necessary irregularity in its shape, also 45 owing to the necessary excessive thinness of the scraper, it is necessary to use some non-resonant material, since a metal scraper would ring and grate and make so much noise as to be very undesirable. The operation of the foot shaped support or cam is merely to guide the meat as it approaches the knife, and to support the slice as it is being cut, thus preventing the rending or tearing of the meat and consequent rough 50 and irregular slices.

While I have illustrated my invention as applied to a slicing machine designed primarily for the slicing of meat, bread and other such objects and materials, still it is 60 quite evident that the same invention might equally well be applied to any device wherein rotary cutting or grinding wheels are used such as saws, grinders and the like.

I claim:

In a slicing machine the combination of a rotary knife having a beveled cutting edge with an inclined scraper across and in contact with said edge and sharply inclined thereto and an arc-shaped deflector in close proximity to the knife at the inner margin of the effective cutting edge said scraper and deflector mounted so as to be simultaneously movable to and from the knife.

Signed at Chicago, Illinois, this 28th day 75 of March 1912.

AUGUST R. LUSCHKA.
